Attorney

UNITED STATES PATENT OFFICE.

HOWARD E. BROWNING, OF CHESTER, ILLINOIS.

AIR HEATER.

Application filed February 18, 1924. Serial No. 693,680.

To all whom it may concern:

Be it known that HOWARD E. BROWNING, a citizen of the United States, residing at Chester, in the county of Randolph and State of Illinois, has invented certain new and useful Improvements in Air Heaters, of which the following is a specification.

This invention relates to air heaters adapted to be used in conjunction with furnace structures, and it consists in the novel features hereinafter described and claimed.

An object of the invention is to provide an air heater of simple structure having maximum area of air heating surface where-
15 by economy may be effected in the use of fuel in that an increased area of heat absorbing surface is presented to the fire and products of combustion thereof.

In structure, the air heater includes a unit having a pocket, or a series of pockets, the opening or openings of which are disposed above the fire pot of the furnace. These pockets receive the products of combustion from the fire pot and the pockets
25 are provided at their upper portions with an opening or openings, which are adapted to communicate with a smoke pipe, whereby the products of combustion after being deprived of heat units, are discharged from the pockets into the smoke pipe.

The pockets are spaced from each other and disposed in parallel relation and a hood is disposed over the pockets and is provided with skirt portions extended down along the sides of the fire pot to the base of the furnace. The skirt portions are provided in the vicinity of their lower edges with openings which admit cool air from the vicinity of the floor level. This air
35 passes up along the sides of the fire pot and is preheated, it then passes through the spaces between the pockets and is superheated and in such condition may rise from the top of the furnace and circulate about the building or structure in which the heater is located.

The features for permitting the products of combustion to escape from the pockets may be of various forms and arrangements. In one arrangement, the products of combustion may escape from the end walls of the pockets, in another arrangement the products of combustion may escape from the end walls and top walls of the pockets, and in a third arrangement, the products

of combustion may escape from the top walls only of the pockets.

In the accompanying drawings:—

Figure 1 is a vertical sectional view showing one form of the air heater applied to the fire pot of a furnace.

Figure 2 is a transverse sectional view of the form of the invention as illustrated in Figure 1, and cut on the line 2—2 thereof.

Figure 3 is a top plan view of the form 65 of air heater as shown in Figure 1.

Figure 4 is a detail sectional view showing a modified form and arrangement of the pockets of the air heater.

Figure 5 is a top plan view of the arrangement and form of pockets as shown in Figure 4.

Figure 6 is a perspective view of a further modified form of pockets which may be employed in the heater.

In the form of the invention as illustrated in Figures 1, 2 and 3 of the drawing, the same includes pocket members 1 which are preferably integrally joined together and spaced from each other and disposed in parallel relation. The mouths 2 of the pocket members are downwardly disposed and located above the fire pot 3 of a furnace structure. The pocket members 1 are provided at their vertical side edges and in the vicinity of their upper edges with outlet openings 4 which register with a smoke pipe carried at the upper portion of a hood 6 which is disposed over the pocket members 1. The hood 6 is provided at its opposite sides and in the vicinity of the upper edge of the fire pot with openings 7 and skirt portions 8 are disposed over the said openings 7 and extend downwardly from the sides of the hood along the body of the 85 furnace and spaced therefrom and terminate at their lower edges at the base of the furnace. The said skirt portions 8 are provided just above the floor level with air inlet openings 9.

The operation of the heater is as follows. The products of combustion from the fire in the fire pot 3, pass up into the pocket members 1 and heat the side walls thereof. The products of combustion pass from the 105 pockets 1 through the openings 4 into the smoke pipe 5 and are carried up the flue in the usual manner. At the same time, cold air enters under the skirt portions 8 through the openings 9, passes up along the sides of 110

the body of the furnace and is preheated. This air passes between the pocket members 1 and is superheated by coming in contact with the heated surfaces thereof and 5 emerges from the furnace at the top of the hood 6.

In the form and arrangement of the air heating apparatus shown in Figures 4 and 5 of the drawings, the same consists of single or individual pocket members 1' having base flanges 10 adapted to enter grooves provided in the side edges of heat resisting bars 11 which are disposed transversely of the fire pot 3.

15 In this form of the invention, the pocket members 1' in addition to having the outlet openings 4', provided at the upper portions of their end edges, are also provided at their top sides and at points midway between their ends with outlet openings 12 and consequently the products of combustion may be taken from the pocket members at the ends thereof and at the top side thereof at points midway between the ends.

25 In the form of the invention as illustrated in Figure 6 of the drawings, the pocket member 1', is devoid of the exit openings at the upper portions of its end edges and is provided at its top side with an outlet opening 30 12', the said opening being located at a point midway between the ends of the said pocket member. In this form of pocket member, the products of combustion are permitted to escape from the same at the top thereof 35 and at a point midway between the ends thereof only.

In the forms of the invention as illustrated in Figures 4, 5 and 6, the air is heated in the same manner as that described in 40 conjunction with the form of the invention as illustrated in Figures 1, 2 and 3 and the products of combustion contribute their heat units to the surfaces of the pocket members

in the same manner as that described in connection with the description given of the 45 form of the invention shown in Figures 1, 2 and 3.

In the form of the invention as illustrated in Figures 1, 2 and 3, the pocket members are preferably formed from sheet metal. In 50 the forms of the invention as shown in Figures 4, 5 and 6, the pocket members are preferably composed of cast metal.

Having described the invention, what is claimed is:

1. An air heater for use in conjunction with a furnace comprising pocket members having mouths adapted to be disposed above the fire pot of the furnace, the pocket members being spaced from each other and disposed in parallel relation, the pocket members being provided at their upper portions with outlet openings through which the products of combustion may make exit, a hood disposed over the pocket members and provided at its sides with openings, skirt portions depending from the hood and disposed over the openings therein and adapted to extend along the sides of the furnace, the said skirt portions being provided in the 70 vicinity of their lower edges with air inlet openings.

2. An air heated adapted for use in conjunction with a furnace comprising pockets provided with mouths adapted to be disposed above the fire pot of the furnace, said pockets being provided at their upper portions with openings through which the products of combustion may make exit, said pockets being provided at their lower edges 80 with flanges and grooved bars interposed between the flanges of the adjacent pockets, the grooves in the bars receiving the edge portions of the flanges.

In testimony whereof I affix my signature.
HOWARD E. BROWNING.
